UNITED STATES PATENT OFFICE.

HARRY KELLER, OF PHILADELPHIA, PENNSYLVANIA.

PNEUMATIC HAMMER.

1,035,358.

Specification of Letters Patent. Patented Aug. 13, 1912.

Application filed October 22, 1908. Serial No. 459,075.

To all whom it may concern:

Be it known that I, HARRY KELLER, a citizen of the United States, residing in the city and county of Philadelphia, State of Pennsylvania, have invented a new and useful Pneumatic Hammer, of which the following is a specification.

The object of my present invention is to design a pneumatic tool wherein I am enabled to eliminate the delicate and intricate parts, the life of which are comparatively short and which are expensive to replace, and I employ in lieu thereof a simplified construction which gives in practice the highest possible efficiency without the very objectionable feature of such parts becoming so worn that it is necessary to replace the same within a short period of time.

To the above ends my invention consists of a novel construction of a pneumatic tool in which the handle or cylinder head is fastened to the cylinder by means of a tapered thread which, in conjunction with a spring box and spring interposed between the handle or valve box, enables me to dispense with the clamping devices, which have heretofore been deemed essential in devices of this character.

It further consists of a novel construction of a pneumatic tool wherein the valve casing is maintained in position against the cylinder by means of a novel construction of a resilient casing, whereby an air-tight connection between the valve casing and the cylinder is maintained at all times and after the handle has been secured in assembled position, owing to the provision of the tapered thread in the head block thereof, there will always be a rigid air-tight connection between such head block and the cylinder and the constant wear of the threads and the loosening of the head block from the cylinder, thereby permitting the motive fluid to escape, is positively prevented.

It further consists of a novel construction of a differential piston having a constant pressure on the smaller differential area and a varying pressure on the larger pressure area, whereby there is never at any time any pressure on the striking point of the piston or the working tool, and the ports and passages at the front or forward end of the piston chamber exhaust directly into the atmosphere.

It further consists of a novel construction of a distributing valve having differential pressure area with constant pressure of the motive fluid on the smaller area and an intermittent pressure of the motive fluid on the larger area, thereby assuring a positive movement of the valve and the accurate control of the reciprocating piston.

It further consists of other novel features of construction, all as will be hereinafter fully set forth.

For the purpose of illustrating my invention I have shown in the present instance but one form thereof, since the same has been found in practice to give satisfactory and reliable results, and is at present preferred by me, although it is to be understood that the various instrumentalities of which my invention consists can be variously arranged and organized and that my invention is not limited to the precise arrangement and organization of these instrumentalities as herein set forth.

Figure 1 represents a longitudinal sectional view of a pneumatic tool embodying my invention. Fig. 2 represents a sectional view of Fig. 1, the handle and the retaining device for the valve casing having been removed. Fig. 3 represents a perspective view of the valve in detached position. Fig. 4 represents a longitudinal section of Fig. 3. Fig. 5 represents an end view of the valve. Fig. 6 represents a sectional view on line $x-x$, Fig. 2. Fig. 7 represents a longitudinal section of another embodiment of my invention, the same type of piston and valve being employed; certain other details of the construction being slightly modified to adapt the tool for different kinds of work.

Similar numerals of reference indicate corresponding parts in the figures.

Referring to the drawings:—In all the embodiments of my invention, as herein shown, the distributing valve and also the piston is shown as having a differential construction and the valve and the piston are adapted to move in an opposite direction when the tool is operating.

1 designates the cylinder of a pneumatic tool embodying my invention, the same being provided with different diameters 2 and 3 within which reciprocates the differential piston 4, the same comprising differential heads 5 and 6 connected by an annular groove 7. The handle 8 is provided with

a head block 9 having a tapered thread 10, which engages with a similar tapered thread of the cylinder 1, in order to secure the parts in assembled position. The motive fluid, 5 which would preferably be compressed air, enters the handle through the passage 11, which is controlled by means of the manually actuated throttling device 12 of any usual or conventional type. The motive fluid then passes through the aperture 12 in the 10 spring casing 13 and thence into the distributing chamber 14. The spring casing 13 is seated in a chamber 15 in the head block 9 and is provided with an annular groove 16 in which is located suitable packing material 17, which is maintained in engagement with the walls of the chamber 15 owing to the pressure of the motive fluid passing through the ports 18, which communicate with the interior of the casing 13 and with the annular groove 16, it being seen that a spring 19 abuts against the inner end of the chamber 15 and against the bottom of the casing 13, thereby causing said casing 20 to be firmly seated against the valve box 20 and causing the movable bottom 21 thereof to abut against the inner end of the cylinder 1 and form an air-tight connection at such point when the parts are in assembled position, as will be evident from Fig. 1.

When the parts are in the position seen in Fig. 1, the piston is in extreme rearward position and the valve 22 has a constant pressure on its small head 23 and since there 35 is no pressure on the larger head 24, the valve will be seated in the position seen in Fig. 1. The valve 22, in the present instance, is closed at one end as indicated at 25, and is provided with an annular groove 26 at its closed end, it being seen that the heads 23 and 24 are joined by a neck 27 and the closed end 25 is preferably rounded, as most clearly seen in Figs. 2 and 4. The smaller diameter 23 of the valve is adapted 40 to travel in the smaller diameter 28 of the valve box 20 while the enlarged diameter 24 is adapted to travel in the enlarged diameter 29 of the valve box 20, it being noted that the motive fluid has free access to the distributing chamber 14. When the parts are 45 in the position seen in Fig. 1, the motive fluid may pass through ports 30 into the passages 31, which open into the enlarged piston chamber 2 and acting against the enlarged head 5 of the piston 4 will cause the 50 same to be moved forwardly into the position seen in Fig. 2 and a blow will be imparted to the reduced end 32 of the plunger 33 and cause the latter to impart a blow to 55 the shank of the working tool 34, which extends through the apertured bushing 35, which has preferably a driving fit in the end 36 of the cylinder 1, it being seen that the enlarged head 37 of the plunger 33 moves 60 within a chamber 38 which is preferably of

a different diameter than the aperture 36. If desired the plunger 33 may be dispensed with and the piston will impart its blow directly to the working tool.

The motive fluid in front of the piston 4 may exhaust through port 39, passage 40 and passage 41 in the valve casing 13 to the atmosphere, as will be apparent from Fig. 2.

As soon as the piston 4 assumes the position seen in Fig. 1, the motive fluid may pass through port 42, passage 43, port 44, around the annular groove 7 of the piston 4 and through port 45 and passage 46, through port 47 in the valve box bottom 21 and acting against the enlarged head 24 of the valve 22 will cause the valve to assume the position seen in Fig. 2, at which time the smaller head 23 will prevent the motive fluid passing from the distributing chamber 14 to the port 30, as will be understood by reference to Fig. 2 and the motive fluid may exhaust through ports 48 into which latter the passages 41 discharge.

The motive fluid within the valve casing 90 may exhaust through the passages 31, ports 30 and ports 48 to the atmosphere.

The piston is returned to its rearward position, as seen in Fig. 1 owing to the pressure of the motive fluid against the shoulder formed by the groove 7 of the enlarged head 5. As soon as the front end of the piston uncovers the port 49 the pressure under the valve acting against the larger head 24 thereof will be released through the port 47, passage 46, port 49, piston chamber 3, port 39, passages 40 and 41, thence through the main exhaust ports 48 to the atmosphere and the constant pressure on the smaller head 23 of the valve will cause said valve to be seated in its forward position. It will be noted that there is always a constant pressure of live motive fluid through port 42, passage 43 and port 44.

In the embodiment seen in Fig. 7, I have shown a construction wherein the working tool is of the spindle type, the piston imparting its blow directly thereagainst, but I do not desire to be limited to any particular construction of the working tool, since the form of such tool varies in practice in accordance with the work which is to be accomplished. In this embodiment, the ports and passages are similar to those already described with respect to Figs. 1 to 6 inclusive and I also employ a differential piston and a differential valve, the construction of which corresponds to that seen in said figures except that the same is constructed upon a larger scale. In this embodiment, 50 designates a cylinder provided with the differential diameters 51 and 52, within which the heads 53 and 54 of the piston 55 are adapted to reciprocate, said heads 53 and 54 being connected by the neck 56. The shank 125

of the working tool 57 extends directly into the forward end of the chamber 52 so that the piston will impact directly thereagainst, and a free exhaust port 58 to the atmosphere. 5 There is provided at the forward end of the chamber 52, 59 designates a cylinder head which is provided with a tapered thread 60 adapted to engage with the tapered thread 61 of the casing 50. The cylinder head 59 10 is provided with an inlet port 62 and with an exhaust port 63. In order to positively prevent any relative movement of the cylinder head 59 and the cylinder 50, I provide a clamping ring 63 having a lug 64 adapted to 15 be seated in a recess 65 in said cylinder head 59, said clamping ring 63 being maintained in assembled position by means of a suitable fastening device 66 of the usual construction. Since the operation of this embodiment of 20 my invention is similar to that already described and since the construction of the ports and passages and of the piston and differential valve 67 is the same, I have deemed it unnecessary to further describe 25 the same.

I wish to call particular attention to the manner in which the valve casing is angularly recessed in proximity to the ports 30, since by such a construction the passages 30 through the valve casing may be readily drilled in such a manner that there are no extra holes or passages through the casing which require plugging, as is necessary in the usual construction of such casings, and 35 thereby I am enabled to eliminate the liability of such plugs working loose due to the excessive vibration, with consequent leakage of the motive fluid and loss of power in the pneumatic tool.

40 Having thus described my invention, what I claim as new and desire to secure by Letters Patent, is:—

1. In a pneumatic tool, the combination with a cylinder having a tapered thread, 45 of a handle having a recessed head block engaging said thread, a valve box within said head block, and a spring pressed casing intermediate said valve box and one end of said recess.

50 2. In a pneumatic tool, the combination with a cylinder having a tapered thread, of a handle engaging said thread, a valve box within said handle, a spring pressed casing

for maintaining said valve box against said cylinder, and packing carried by said casing. 55

3. In a pneumatic tool, the combination with a cylinder having a tapered thread, of a handle engaging said thread, a valve box within said handle, a spring pressed casing for maintaining said valve box against said cylinder, packing carried by said casing, and means for conducting motive fluid to said packing.

4. In a pneumatic tool, the combination with a cylinder having a tapered thread, of a handle having a head block engaging said thread, said head block being recessed, a valve box within said recess, a hollow casing within said recess intermediate said box and one end of said recess, packing carried by 70 said casing and engaging the walls of said recess, means for conducting motive fluid to said packing, and resilient means co-acting with said casing for holding said valve box in air tight engagement with said cylinder. 75

5. In a pneumatic tool, the combination with a cylinder having a tapered thread, of a handle having a head block engaging said thread, said head block having a recess 80 therein to which motive fluid is admitted, a valve box within said recess, a hollow casing contiguous said valve box and provided with an external groove having ports communicating therewith and with the interior 85 of said casing, packing in said groove, and a spring engaging said casing and one end of said recess.

6. In a pneumatic tool, the combination with a cylinder having a tapered thread, of a handle having an apertured block engaging said thread, said head block having a differential bore to which motive fluid is admitted, a valve box within one of said diameters, an apertured casing in the other 95 of said diameters and engaging said valve box, said casing being provided with packing on its periphery, means for admitting motive fluid to said packing; and a spring engaging said casing and causing the latter 100 to maintain said valve box in air tight engagement with the end of said cylinder.
